DESIGN FOR A BOTTLE

Jacob Payne, Manhasset, N. Y.

Application December 9, 1940, Serial No. 97,180

Term of patent 3½ years

To all whom it may concern:

Be it known that I, Jacob Payne, a subject of Great Britain and residing in the town of Manhasset, in the county of Nassau and State of New York, have invented a new, original, and ornamental Design for Bottles, of which the following is a specification, reference being had to the accompanying drawing, forming part thereof.

Fig. 1 is a front view of the bottle showing my new design;

Fig. 2 is a side elevational view; and
Fig. 3 is a top plan view thereof.

I claim:

The ornamental design for a bottle, as shown.

JACOB PAYNE.
